Atty.

UNITED STATES PATENT OFFICE.

JOHN S. S. FULTON, OF CHICAGO, ILLINOIS, ASSIGNOR TO UNITED STOKERS CORPORATION, A CORPORATION OF ILLINOIS.

HOPPER FOR AUTOMATIC STOKERS.

1,278,325

Specification of Letters Patent. Patented Sept. 10, 1918.

Application filed October 31, 1917. Serial No. 199,576.

To all whom it may concern.

Be it known that I, JOHN S. S. FULTON, a citizen of the United States, residing at Chicago, in the county of Cook and State of Illinois, have invented certain new and useful Improvements in Hoppers for Automatic Stokers, of which the following is a full, clear, and exact specification.

My invention relates to mechanical stokers, and the improvements hereinafter described relate more particularly to the control of the fuel feed from the hopper to the grate, and to the construction of the hopper and controlling mechanism.

In mechanical stokers great difficulty has been experienced due to the overheating and burning out of parts of the hopper, thereby causing loss and inconvenience, and also due to the coal or other fuel in the hopper becoming ignited and thereby interfering with its proper feed.

Furthermore, there has been considerable difficulty, especially in horizontal types of automatic traveling-grate stokers, should it become necessary to stoke by hand, in obtaining direct access to the fuel on the grate in the combustion chamber. Heretofore, it has been the custom to empty the hopper and remove the front portion entirely.

The object of my invention is to overcome the difficulties above enumerated, and I accomplish this by the novel apparatus which will be illustrated in the accompanying drawings and described in the following specification.

In one aspect my invention consists in so mounting the front wall of a fuel hopper that it can be moved, with very little effort, to cut off the supply of fuel from the hopper to the grate, and open a space above the grate to permit direct access to the surface of the grate in the combustion chamber. In another aspect my invention consists in so constructing and arranging the fuel controlling gate, and the parts of the structure adjacent thereto, that heat insulating passageways are formed to protect the portions of the gate that are in contact with the fuel in the hopper and the portion of the hopper framework adjacent the ends of the gate. These passageways preferably form conduits for air streams which enter the combustion chamber above the surface of the fuel, and

assist in the combustion of the volatile matter driven from the fresh fuel.

In the accompanying drawings—

Figure 1 is a sectional elevation of a chain grate stoker equipped with my improved hopper construction;

Fig. 2 is a fragmentary sectional elevation of the hopper showing the pivotally mounted front wall in horizontal position;

Fig. 3 is an elevation of the interior of the metallic framework of the grate with the firebrick or refractory material removed;

Fig. 4 is a perspective view of the hopper end of the stoker, removed from the combustion chamber, and showing the relative position of the adjustable gate, air-cooled plates, etc.

Fig. 5 is a sectional elevation on an enlarged scale of a portion of the side wall of the hopper containing one of the air-cooled guide plates for the gate, the section being taken along the line 5—5 of Fig. 8;

Fig. 6 is an end elevation of one of the air-cooled guide plates;

Fig. 7 is a side elevation of the plate shown in Fig. 6; and,

Fig. 8 is a sectional plan view of the guide plate and its supporting wall along the line 8—8 of Fig. 5.

Referring now to the drawings, it will be seen that my improved hopper mechanism is shown in connection with a chain grate type of automatic stoker, the chain links 10, supporting grate elements 11, through the agency of the cross bars 12. The chain links are supported on and are driven by the sprocket wheels 13 mounted on the drive shaft 14. The specific structure of this chain grate and its driving and adjusting mechanism form no part of the invention covered by this application, but form the subject matter of a copending application filed December 6, 1917, Serial Number 205,869.

Located above the grate is my improved hopper. This hopper is formed by the side walls 15 of the relatively stationary framework, the normally inclined front wall 16, and the rear wall consisting essentially of the vertically adjustable gate 17 and the elements co-operating therewith.

The hopper front wall 16 is pivotally mounted at 18 on the lugs 19 attached to the

hopper side frames 15. These lugs are located so as to support the hopper front wall slightly below a horizontal line through its center of gravity. The front wall is secured in its normal inclined position by the hooks 20, pivotally mounted on the side walls. When it is desired to remove the fuel from the hopper or stoke the fire by hand, or permit access to the fuel on the 10 grate in the combustion chamber, the hooks 20 are raised and the hopper front wall 16 pivots about the supporting lugs 19 until the lower portion 21 of the front wall strikes the projecting lugs 22 on the side 15 walls, assuming the horizontal position shown in Fig. 2.

In connection with the use of certain fuels, difficulty is sometimes experienced due to the air spaces in the grate bars becoming 20 clogged with fine ashes. To remove these ashes I have provided a series of strong steel wire brushes 24 extending across the entire front wall, and secured thereto in such a manner that the wire points will drag into 25 the air spaces of the grate bars a sufficient distance to keep them entirely clear. The supporting brackets 25 for these brushes are provided with means, such as slots 26, which are engaged by the bolts 23, so that the 30 brushes may be lowered from time to time as the points become worn off. When the front wall 16 is thrown into the position shown in Fig. 2, the brushes will be raised so as not to interfere with the hand stoking 35 of the fire.

The gate 17 forms the main portion of the rear wall of the fuel hopper. This gate is primarily used for the purpose of regulating the depth of the fuel upon the grate 40 within the furnace or to vary the rate of fuel feed. The gate is held in a suspended position by chains 27 attached to a shaft or drum 28, which is rotated by the ratchet and pawl mechanism 29, operated by the lever 45 30, and held in adjusted position by pawl 31, (Fig. 4). This device serves as the means for raising or lowering the gate 17, as required to meet operating conditions. It must be understood, however, that certain 50 features of my invention are applicable to a hopper with a stationary rear wall or a non-adjustable gate where other means are employed for adjusting the depth of fuel on the grate.

55 The gate consists of a box-like metallic framework 32 supporting a lining or facing 33 of fire brick or other refractory material. This firebrick coöperates closely with the outer surface of the arch 34. The firebrick 60 lining 33 is held from coming in direct contact with the metallic framework 32 by any suitable means, here shown as ribs or lugs 35 on the inner surfaces of the metallic framework, thereby forming heat insulating 65 air passageways through which a circ-

tion of air is constantly maintained between the two surfaces, thus preventing transmission of heat from the firebrick lining (which is at all times, during operation, red hot) to the metallic framework and destroying it, 70 as it very frequently the case with other stokers. The lower portion of this framework is made up of a plurality of angular members 32^a adjustably mounted on the upper portion. 75

The fuel in the hopper is prevented from coming in direct contact with the upper portion of the framework of the gate by an arrangement of plates, which provide for a circulation of air for cooling purposes. 80 These plates, while excluding fuel from the air passageways, permit the gate to be raised or lowered without interference. The plate 40, extending across the hopper, prevents fuel from reaching the gate from the top. 85 To the front edge of this plate 40 is attached the depending stationary plate 41. To the framework of the gate is attached the vertical plate 42, coöperating with, and overlapping plate 41. It will, therefore, be 90 evident that no fuel can come in direct contact with the firebrick or with the upper portion of the gate proper. This is a very vital feature, as constant trouble is experienced in other stokers due to the gate becoming overheated, igniting the fuel in the hopper, causing it to fuse to the gate and stop the feed of fuel. If this burning fuel or fused mass is not quickly poked or shoveled out of the hopper, it will cause the 95 destruction of the gate.

By my improved hopper construction, I provide heated air for the combustion of the volatile matter of the fuel within the furnace just after the fuel enters the combustion chamber. Air is admitted from the atmosphere through the openings 43 in each side wall of the hopper into the chamber formed beneath the plate 40 and above the top of the gate, thence to the passageway 105 44 between the plate 42 and the framework 32. The air due to the natural draft in the combustion chamber passes downward behind the plates 41 and 42, and enters a series of openings 45 in the metallic framework 110 of the gate, leading to the heat insulating passageways 46 between the framework of the gate and the red hot firebrick lining. The air continues its movement through 115 these passageways in contact with the firebrick until it reaches the lower edge of the gate adjacent the combustion chamber, where the air, heated in its passage, is evenly diffused over the surface of the fuel and through the distilled volatile matter, thereby assisting in the combustion of the latter. The course of the air currents is indicated by arrows. 120

125 Mounted in the side walls 15 opposite the ends of the gate are the removable air-

cooled guide plates 50. These plates are held in position in said side walls by means of the bolts 51, but are spaced from the side walls by the lugs 52 and flanges 52^a. The vertical edge of each plate adjacent the combustion chamber is provided with a plurality of slots or openings 53, which communicate with the passageway 54 formed between the plate and the side wall. Streams of air for the purpose of cooling these guide plates, and thereby preventing the hopper frame and the ends of the gate from becoming excessively heated, are forced by atmospheric pressure (due to the natural draft in the combustion chamber) through the openings 55 into the passageways 54, and thence through the openings 53 into the combustion chamber. These streams of air, heated in their passage through the guide plates, assist in the combustion of the volatile matter driven from the fuel on the grate surface. Each of these guide plates is provided with a flange 56, projecting over the edge of the grate, for the purpose of preventing fine fuel sifting down between the frames and grates before it becomes ignited, after which no sifting will occur.

The lower corners of the gate are cut away at 48 so as to permit a greater amount of fuel to be fed from the hopper to the grate surface along each side. The additional amount of fuel fed along the sides of the grate is so proportioned that by the time the fuel reaches the rear of the furnace the fire line is even. Therefore, there is no danger of the side grate elements becoming bare, or of unburned fuel being carried over the rear throughout the central portion of the grate, resulting from the faster burning of the fuel along the sides; a well-known fact to all operating engineers, and usually compensated for by poking.

Although I have illustrated and described the preferred embodiment of my invention, and its application to a particular type of stoker or furnace, it must be understood that many modifications and adaptations to other types of stokers or furnaces may be made without departing from the spirit of the invention, or its scope as set forth in the appended claims.

What I claim as new is:

1. In an automatic stoker, a grate, and a hopper through which fuel is fed to the grate, said hopper being provided with a pivotally mounted front wall, and a plurality of wire brushes mounted on the lower side of said front wall and contacting with the upper surface of the grate.

2. In an automatic stoker, a grate, and a hopper through which fuel is fed to the grate, said hopper being provided with a pivotally mounted front wall, a plurality of wire brushes mounted on the lower side of

said front wall and contacting with the upper surface of the grate, and means for adjusting said brushes relative to said front wall.

3. In an automatic stoker, a grate, and a hopper through which fuel is fed to the grate, said hopper being provided with a pivotally mounted front wall, a plurality of wire brushes mounted on the lower side of said front wall and contacting with the upper surface of the grate, and means for moving said front wall into a horizontal position, thereby moving the brushes out of contact with the grate surface.

4. In an automatic stoker, a grate and a hopper through which fuel is fed to the grate, and a plurality of wire brushes mounted in front of the front wall of said hopper, and contacting with the upper surface of the grate.

5. In an automatic stoker, a grate, a hopper through which fuel is fed to said grate, an adjustable gate in said hopper for controlling the rate of fuel feed, one of the walls of said hopper being movable to seal the bottom of the hopper and permit direct access to the surface of the grate when the gate is open.

6. In combination, a combustion chamber, a grate, a hopper through which fuel is fed to the grate, a grate in said hopper, said gate being provided with means whereby a stream of air is fed into the combustion chamber at the surface of the fuel on the grate, and means permitting streams of air to enter the combustion chamber at the ends of said gate.

7. In combination, a combustion chamber, a grate, a hopper through which fuel is fed to the grate, a gate in said hopper adjustable to vary the rate of fuel feed, and means permitting streams of air to enter the combustion chamber at the ends of said gate adjacent to the side walls of the combustion chamber.

8. In combination, a combustion chamber, a grate, a hopper through which fuel is fed to said grate, a vertically adjustable gate in said hopper for varying the rate of fuel feed, stationary guide plates on the walls of the combustion chamber at the ends of the gate, each guide plate being spaced from the walls of the combustion chamber to form passageways for permitting streams of air to pass into the combustion chamber, thereby preventing said guide plates and the ends of said gate from becoming excessively heated.

9. In combination, a combustion chamber, a grate, a hopper through which fuel is fed to said grate, a gate in said hopper adjustable to vary the rate of fuel feed, and means separate from said gate for cooling the side walls of the combustion chamber adjacent the ends of the gate.

10. In combination, a combustion chamber, a grate, a hopper through which fuel is fed to said grate, a gate in said hopper adjustable to vary the rate of fuel feed, guide members for the ends of said gate in the side walls of said combustion chamber, said guide members being provided with passageways through which fluid may pass for cooling the guide members.
11. In an automatic stoker, a grate, a hopper having a rear wall provided with a gate, means for adjusting the gate vertically to vary the rate of feed of the fuel to the grate, said gate being provided with heat insulating air passageways separating the portion of the gate which is adjacent the fuel in the hopper from the remainder of the gate.
12. In an automatic stoker, a grate, a hopper having a rear wall provided with a gate located above the grate, means for adjusting the gate vertically to vary the rate of feed of the fuel to the grate, said gate being made up of a metallic framework and a removable facing of refractory material with heat insulating passageways between the refractory material and the metallic framework, and a stationary plate overlapping said metallic framework and co-operating therewith to prevent the entrance of fuel from the hopper into said heat insulating passageways.
13. In an automatic stoker, a horizontally movable grate capable of operating in a combustion chamber, a hopper above said grate provided with a vertically adjustable gate to vary the rate of feed of fuel to the surface of said grate, and means carried by said gate whereby a stream of air is supplied to the upper surface of the fuel on said grate to assist in the combustion of the volatile matter driven from the fuel as it enters the combustion chamber.
14. In an automatic stoker, a horizontally movable grate capable of operating in a combustion chamber, a hopper above said grate provided with a vertically adjustable gate to vary the rate of fuel to the surface
- of said grate, and means carried by said gate whereby a stream of air is supplied to the upper surface of the fuel on said grate to assist in the combustion of the volatile matter driven from the fuel as it enters the combustion chamber, said means including passageways in said gate communicating with passageways in the stationary portion of said hopper and opening into the combustion chamber along the lower edge of said gate.
15. In an automatic stoker, a horizontally movable grate capable of operating in a combustion chamber, a hopper above said grate provided with a vertically adjustable gate to vary the rate of feed of fuel to said grate, said gate being formed of a box-like framework comprising vertically adjustable angular metallic members provided with ribs, and a removable facing of standard fire brick mounted upon said ribs, and clamped in position between said angular members, whereby the refractory facing is spaced from the framework, and insulating air passages are formed which prevent excessive heating of the portion of the metallic framework which is in contact with the fuel in the hopper.
16. In an automatic stoker, a grate capable of operating in a combustion chamber, a hopper provided with an adjustable gate to vary the rate of feed of fuel to said grate, said gate being made up of a metallic framework including vertically adjustable angular clamping members provided with spacing ribs, and a removable facing of standard fire brick held between said clamping members but spaced therefrom by said ribs to form insulating air passageways between the fire brick and the metallic framework, thereby preventing excessive heating of that portion of the metallic framework which is in contact with the fuel in the hopper.

In testimony whereof I affix my signature.

JOHN S. S. FULTON.
